[57] CLAIM

The ornamental design for a combined hearing aid and
geriatric amplifier, as shown and described.

DESCRIPTION

FIG. 1 is a top right perspective view of a combined
hearing aid and geriatric amplifier, showing my new
design;

FIG. 2 is a top left side perspective view thereof;
FIG. 3 is a bottom left perspective view thereof, with
the battery compartment door in closed position; and,
FIG. 4 is a bottom left perspective view thereof, with
the battery compartment door in open position.

FIG. 4
